UNITED STATES PATENT OFFICE.

EARL F. BALDWIN, OF GARDNER, MASSACHUSETTS, ASSIGNOR TO AMERICAN FIBRE CORPORATION, OF GARDNER, MASSACHUSETTS, A CORPORATION OF MASSACHUSETTS.

LET-OFF MECHANISM FOR LOOMS.

Original application filed December 12, 1921, Serial No. 521,624. Divided and this application filed November 25, 1922. Serial No. 603,339.

To all whom it may concern:

Be it known that I, EARL F. BALDWIN, a citizen of the United States, residing at Gardner, in the county of Worcester and 5 State of Massachusetts, have invented new and useful Improvements in Let-Off Mechanism for Looms, of which the following is a specification.

This invention relates to looms particularly designed for weaving fiber such as 10 strands formed from paper strips, this application being a division of my application Serial No. 521,624 filed December 12, 1921, for looms and relating to the let-off 15 mechanism by which the warp strands are permitted to feed to the weaving mechanism, this mechanism acting to separately tension each strand but allowing all to move as a unit during the shedding.

20 For a more complete understanding of this invention, together with further objects and advantageous details and combinations of parts, reference may be had to the accompanying drawings in which—

25 Figure 1 is a fragmentary rear elevation of the upper portion of the loom showing the subject matter of the invention.

Figure 2 is a section on line 2—2 of Figure 1.

30 In the machine more fully shown and described in the above mentioned parent application for patent, of which the present application is a division, shedding may be effected progressively between the sides and 35 center of width of the fabric by properly timing opposite ends of the harnesses and because of this action of the mechanism causing progressive shedding, the warp threads must be drawn through the tension 40 mechanism at somewhat different times. For this reason means for applying tension individually to the warp strands has been provided. As shown in the drawings, between the end frames 1 and 2 is positioned

45 a bar 220 of somewhat T-shape in cross section. Passing through the end frame members 1 and 2 are bolts 221 and 222 which engage within suitable sockets in the ends of the bar 220 and serve to pivotally mount 50 this bar. Seated on the upper face of the bar 220 is a bar 223 having a series of openings 224 therethrough, one for each strand

of warp material and positioned back of each opening 224 is an eye 225 flared outwardly at its rear end through which the 55 strands may be threaded. Within each recess or opening 224 is pivoted a tension lever 226, the inner end of which is urged downwardly toward the bar 220 to engage on the strand by means of a spring 227 60 seated in a socket 228 thereabove and the tension of which may be adjusted by means of a plug 229 threaded in the upper end of this socket. By grasping the upper end of lever 226 it may be rocked upwardly out of 65 engagement with the strand so that the strand may be fed therethrough by hand as in threading the machine. Extending from opposite ends of the bar 223 are arms 230 which project forwardly over the frame portions 1 and 2 and terminate in vertically disposed socketed portions 231 within which are housed coil springs 232 which bear on the upper faces of the frame portions 1 and 70 2. The tension on these springs may be 75 regulated by means of screw rods 233 threaded through the upper ends of the portions 231 and having lock nuts 234 thereon for fixing them in adjusted position. The extent to which these arms 230 may be swung 80 downwardly toward the upper faces of the frame portions 1 and 2 is adjustably fixed by means of rods 235 threaded through lugs 236 extending forwardly of the portions 231 and striking at their lower ends on the 85 frames. Lock nuts 237 may be employed to fix these rods in adjusted position. As the tension elements 226 engage the strands above the pivot bolts 221 and 222 tension exerted on the strands forwardly through 90 the harnesses (not shown) tends to rock the arms 231 downwardly as far as permitted by the stop rods 235. The springs 232, however, are designed to be much heavier than the tension springs 228 for the individual 95 strands so that the bar will yield as far as permitted by the rods 235, only when all the strands are tensioned at a point not quite sufficient to permit them to feed through their individual tensioning devices. Tension 100 applied to a few strands causes them to pass through their individual tension devices without moving the bar. This permits a yielding of the tensioning device as a whole

to the tension caused by the shedding motion of the harness frames and permits each strand to pay out as it is additionally tensioned due to the progressive shedding action 5 to effect a substantially uniform tension on all the strands; the springs 232 acting as master springs for the entire set of warp strands.

Having thus described certain embodiments of this invention it should be evident to those skilled in the art that many changes and modifications might be made therein without departing from its spirit or scope as defined by the appended claims.

15 I claim:

1. In a loom, a bar, individually adjustable tensioning devices for warp strands carried by said bar, and means for carrying said bar permitting a limited yielding movement thereof in the direction of motion of said strands.
2. In a loom, a tension bar fulcrumed thereon, warp strand guides carried by said bar at one side of said fulcrum, individual tension devices for each warp strand carried by said bar and means for opposing rocking of said bar about its fulcrum due to pull exerted on said strands.
3. In a loom, a tension bar fulcrumed at its ends thereon, warp strand guides carried by said bar at one side of said fulcrum, a tension lever for each guide, a spring pressing each tension lever against the strand in the corresponding guide to oppose drawing of the said strand therethrough and springs opposing the rocking of said bar about its fulcrum due to the pull exerted on said strands.
4. In a loom, a tension bar fulcrumed at 40 its ends thereon and having a limited rock-

ing motion relative thereto, warp strand guides carried by said bar at one side of said fulcrum, a tension lever for each guide, a spring for pressing each tension lever against the corresponding guide to oppose drawing of said strand therethrough, master springs for holding said bar rocked to one limit of motion opposed to the pull exerted thereon by said strands, said springs being so adjusted that said master springs yield only under the combined pull of substantially all said strands insufficient to effect their passage past their tension levers, pull on individual strands causing them to move past their tension levers without affecting said master springs.

5. In a loom having end frames, a tension bar fulcrumed at its ends on said frames for limited rocking motion relative thereto, arms extending from opposite ends of said bar and overlying said frames, master springs seated in sockets in said arms and bearing against said frames to tend to hold said bar at one limit of its rocking, warp strand guides carried by said bar at one side of said fulcrum, means acting to resist the passage of a strand through each of said guides, said resisting means and springs being so related that a pull exerted on substantially all of said strands of less than sufficient value to cause them to move relative to their resisting means causes rocking of said bar against the action of said master springs, while a pull exerted on less than substantially all said strands may reach a value sufficient to cause them to overcome their resisting means without rocking said bar.

In testimony whereof I have affixed my signature.

EARL F. BALDWIN.
